UNITED STATES PATENT OFFICE.

WILLIAM LEE PILKINGTON, OF ST. HELEN'S, ENGLAND, ASSIGNOR TO HIMSELF,
WILLIAM PILKINGTON, THOMAS PILKINGTON, WILLIAM W. PILKINGTON,
RICHARD PILKINGTON, AND GEORGE H. PILKINGTON, OF SAME PLACE.

DESIGN FOR THE ORNAMENTATION OF GLASS.

SPECIFICATION forming part of Design No. 22,173, dated January 31, 1893.

Application filed November 19, 1892. Serial No. 452,583. Term of patent 14 years. Patented in England August 12, 1892,
No. 196,749.

To all whom it may concern:

Be it known that I, WILLIAM LEE PILKINGTON, of St. Helen's, Lancashire, England, have invented a new and original Design for the Surface Ornamentation of Glass, (for which I have obtained Letters Patent in England, No. 196,749, dated August 12, 1892,) of which the following is a full, clear, and exact description.

Reference is to be had to the accompanying drawings forming a part of this specification, in which similar letters of reference indicate corresponding parts in both the figures.

Figure 1 is a face view of a piece of glass embodying my new design; and Fig. 2 is a partial sectional view of the same on the line 2—2 in Fig. 1.

The design consists in the configuration shown. Thus *a* indicates oblique, parallel V-shaped grooves, intersecting as shown and thus dividing the surface into rectangular figures *b*, in each of which is a depression *c*, the four walls of the depression converging to a common center *d*.

I claim:

The design for the surface ornamentation of glass, herein shown and described.

WM. LEE PILKINGTON.
